MATERIAL HANDLING AND LIKE
APPARATUSAugust A. Saul, Pittsburgh, Pa., assignor to Miller
Printing Machinery Co., Pittsburgh, Pa., a cor-
poration of Pennsylvania

Application April 3, 1941, Serial No. 386,651

24 Claims.

(Cl. 271—76)

This invention relates to material handling and like apparatus. It embodies a number of improvement features in operating and control mechanism which may be employed in connection with material handling apparatus but which are also of great utility in other mechanisms and in the field of machinery generally.

The invention will be illustrated as embodied in material handling apparatus and specifically in sheet delivery apparatus for printing presses. Sheet delivery apparatus is apparatus for handling sheets relatively to a printing press while the press is in operation. While the word "delivery" is sometimes used to relate particularly to the handling of the sheets from the press after they have been printed or otherwise acted upon therein, in the present application, unless the context otherwise requires, the word "delivery" is used in a broader sense and applies to the handling of sheets or other material to a printing press or other mechanism acting thereon as well as handling the same away from such press or other mechanism.

The particular mechanism shown in the drawings is a sheet delivery mechanism for delivering sheets which have been printed or otherwise acted upon in a printing or like press away from such press and piling the same. The delivery mechanism is itself bodily movable toward and from the press. Such movement is through suitable control and operating devices and is accompanied by operation of connections between the delivery and press. Means are provided for initiating and terminating relative movements between the delivery and press in predetermined manner. The structure has a number of interrelated novel mechanisms contributing to its utility and ease and efficiency of operation.

Other details, objects and advantages of the invention will become apparent as the following description of a present preferred embodiment thereof proceeds.

In the accompanying drawings I have shown a present preferred embodiment of the invention, in which

Figure 1 is a side elevational view of sheet delivery apparatus with a portion broken away;

Figure 2 is a vertical transverse cross-sectional view taken on the line II—II of Figure 1;

Figure 3 is a detail view of a portion of the structure of Figure 1 with parts omitted for the sake of clearness and showing certain parts in one operative position;

Figure 4 is a view similar to Figure 3 showing the parts in a different operative position;

Figure 5 is a fragmentary top plan view of the apparatus, with a portion broken away;

Figure 6 is a fragmentary horizontal cross-sectional view taken on the line VI—VI of Figure 2;

Figure 7 is a fragmentary vertical longitudinal cross-sectional view to enlarged scale taken on the line VII—VII of Figure 6;

Figure 8 is a fragmentary vertical longitudinal cross-sectional view of a portion of the apparatus taken on the line VIII—VIII of Figure 9;

Figure 9 is a fragmentary plan view of a portion of the apparatus;

Figure 10 is a fragmentary vertical transverse cross-sectional view of a portion of the apparatus taken on the line X—X of Figure 11;

Figure 11 is a fragmentary plan view of a portion of the apparatus, part being shown in horizontal cross section; and

Figure 12 is a fragmentary vertical longitudinal cross-sectional view taken on the line XII—XII of Figure 10.

Referring now more particularly to the drawings, a printing press is indicated diagrammatically at 2 but is not shown in detail since the present invention does not relate to the press structure per se. The press may print upon sheets passed therethrough or it may be equipped with cutting and creasing blades or other instrumentalities for acting on the sheets. Adapted to cooperate with the press and deliver sheets therefrom is a delivery mechanism designated generally by reference numeral 3. The delivery apparatus, which will be hereinafter referred to simply as a delivery, comprises opposed side frame members 4 and cross frame members 5 connected together to support and contain the delivery mechanism. The delivery is separate from the press and is adapted to be moved in a straight line toward and away from the press into and out of cooperative relationship with respect thereto. This provides a working space between the press and delivery. The delivery and press are relatively movable and while in the structure shown the press is stationarily mounted and the delivery moves over the floor the reverse might be the case or the press and delivery might both move.

Extending away from the press and stationarily mounted upon the floor is a supporting and guiding track 6 upon which one side of the delivery is supported and guided through rollers 7. The delivery and track have interfitting portions 8 and 9, respectively, as shown in Figure 2, to insure proper positioning of the delivery at all times and prevent tilting thereof. At its op-

posite side the delivery carries a wheel 10 through which it is supported directly upon the floor. The delivery has bearings 11 and 12, respectively, wherein are rotatively journaled shafts 13 and 14, respectively. The shaft 13 is connected through a universal joint 15 with a screw 16 extending toward the press, and the shaft 14 is connected through a universal joint 17 with a screw 18 extending toward the press. Fixed to the shafts 13 and 14 are sprockets 19 and 20, respectively. Journaled in the delivery are stub shafts 21 and 22 carrying idler sprockets 23 and 24, respectively. Mounted in the delivery is an electric motor 25 whose shaft 26 carries a bevel pinion 27. The bevel pinion 27 meshes with a bevel gear 28 fixed to a driving shaft 29 journaled for rotation in the delivery and to which is also fixed a driving sprocket 30. A sprocket chain 31 meshes with the sprockets 30, 23, 19, 20 and 24, as shown in Figure 2. The mountings for the idler sprockets 23 and 24 may be such that these sprockets or one thereof may be shifted to suitably adjust the tension of the sprocket chain 31.

The press 2 comprises a base 32 having fixedly mounted therein nuts 33 and 34 with which the screws 16 and 18, respectively, are in threaded engagement. The screws 16 and 18 are of the same size, hand and pitch and the sprockets 19 and 20 are of the same size, so when the motor 25 is operated both of the screws 16 and 18 will turn in the same direction at the same speed and will cooperate in exactly similar manner with the respective nuts 33 and 34 through which they pass. Since the nuts 33 and 34 are fixedly positioned in the press base, driving of the screws by the motor 25 will inevitably result in movement of the delivery toward or from the press depending upon the direction in which the motor armature turns. Preferably the motor is a reversing motor so that it may be driven in either direction. Consequently when it is desired to move the delivery toward the press the motor is driven in one direction and when it is desired to move the delivery away from the press the motor is driven in the opposite direction.

Pivoted to the body of the delivery 3 by a cross shaft 35 is a frame 36 carrying one end of each of a plurality of endless conveyors, as will presently be described. The frame 36 is adapted to be swung about the pivot 35 from its generally horizontal operative position, as shown in Figures 1 and 3, to its raised inoperative position as shown in Figure 4. Means are provided, as will presently be described, for raising the frame 36 automatically upon movement of the delivery away from the press and for lowering the frame into operative position upon movement of the delivery toward the press.

The frame 36 comprises a pair of side arms 37, one of which is shown in Figure 1, each fixed to the shaft 35 which is rotatably carried by the delivery body. Extending between the arms 37 near the right-hand ends thereof viewing Figure 1 and rotatably mounted therein are an upper shaft 38 and a lower shaft 39. These shafts are adapted to be driven from the press when the press is in operation and the delivery is in operative position relatively to the press. Mounted on the press cylinder 40 is a ring gear 41 (Figure 1). Due to scale limitations the teeth of the ring gear 41 and the gearing cooperating therewith for driving the shafts 38 and 39 now to be described are not shown in Figure 1, but the pitch lines of the various gears are indicat-

ed by chain lines. Carried by the frame 36 and adapted when the delivery assumes operative position relatively to the press to mesh with the ring gear 41 is a pinion 42. The pinion 42 meshes with a gear 43 which in turn meshes with a pinion 44. The pinion 44 meshes with a gear 45 fixed to the shaft 39. The pinion 44 also meshes with a gear 46 which in turn meshes with a gear 47 fixed to the shaft 38. The size and arrangement of the respective gears is such that when the cylinder 41 turns in the counter-clockwise direction viewing Figure 1 the shaft 39 likewise turns in the counter-clockwise direction and the shaft 38 turns in the clockwise direction, the speeds being such that sheets passing from the cylinder to the delivery are carried forward at approximately the speed at which they are delivered from the cylinder. When the delivery is moved to inoperative position relatively to the press the pinion 42 disengages from the ring gear 41.

Mounted in the delivery 3 is a pair of circular cross rods 48 and 49. Connected with the rod 48 at intervals therealong are brackets 50 each carrying an elongated support 51 extending generally horizontally away from the press. Each support 51 in turn carries a roller mounting 52 on which is rotatably mounted a roller 53. Connected with the rod 49 at intervals therealong are brackets 54 each carrying an elongated support 55 extending generally horizontally away from the press. Each support 55 in turn carries a roller mounting 56 on which is rotatably mounted a roller 57. Each support 55 is slidably within its bracket 54 and is urged toward the left viewing Figure 1 by a coil spring 58 bearing between the bracket and a head 59 on the support. Similarly, each roller mounting 53 is resiliently urged toward the left viewing Figure 1 by spring means concealed within the corresponding support 51 and bearing thereagainst and also bearing against the roller mounting. Consequently each of the rollers 53 and 57 is resiliently mounted for limited movement generally horizontally toward and away from the press and is normally urged away from the press or toward the left viewing Figure 1.

Disposed about each of the rollers 53 and also about the shaft 38 is an endless belt 60. Disposed about each of the rollers 57 and also about an enlargement or roller 61 fixed to the shaft 39 is an endless belt 62. When the shafts 38 and 39 are driven the endless belts 60 and 62 are likewise driven. The rollers 61 are of somewhat greater diameter than the shaft 38 and the rollers 57 are of somewhat greater diameter than the rollers 53. As indicated above, the mechanism for driving the shafts 38 and 39 is such that the belts 60 and 62 move at a speed substantially equal to the peripheral speed of the press cylinder. Sheets pass from the press toward the left viewing Figure 1 between the belts 62 which lie below the sheets and the belts 60 which lie above them. The sheets normally rest upon the belts 62 and are conveyed away from the press toward the left viewing Figure 1 thereby, the belts 60 serving to insure that the sheets do not fly up during movement. The sheets are stripped from the press cylinder by strippers 63 fixed to a stripper shaft 64 operated in well known manner.

As above explained, the frame 36 is pivoted to the delivery by the shaft 35, the frame being fixed to the shaft 35 which is free to turn in its bearings in the delivery. Also fixed to the shaft

35 and extending toward the left therefrom viewing Figure 1 is an arm 65. Pivoted to the arm 65 at 66 is a link 67 which extends generally downwardly and is at its lower end pivotally connected at 68 to a lever 69 having a fulcrum 70 in the delivery and the opposite end of which carries a cam following roller 71. The press has a stationary base 72 which carries an inclined cam 73 the upper active surface of which extends upwardly and toward the left viewing Figure 1.

In Figure 1 the delivery is shown in operative position. When it is desired to move the delivery to an operative position away from the press the motor 25 is energized to turn the screws 16 and 18 in a direction which will result in movement of the delivery toward the left viewing Figure 1. The entire delivery including the frame 36 will move rectilinearly toward the left for a substantial distance while the frame remains in fixed position relatively to the body of the delivery. Such movement will continue until the delivery reaches the position in which the follower 71 engages the cam 73. Further movement of the delivery toward the left is accompanied by riding of the follower 71 up the inclined cam 73 and consequent turning of the lever 69 about its fulcrum 70 in the clockwise direction viewing Figure 1. This results in pulling the link 67 downwardly and the link in turn through the arm 65 causes the frame 36 to pivot in the counter-clockwise direction about the axis of the shaft 35. Thus, as the delivery moves toward the left the frame 36 is automatically pivotally raised from the position shown in Figures 1 and 3 to the position shown in Figure 4. When the frame is in the position shown in Figure 4 the follower 71 has reached the top of the cam 73. Preferably the motor 25 will be stopped by means presently to be described when the parts are in the position shown in Figure 4, although the parts may be suitably designed to raise the frame higher if desired.

When the motor is operated in the opposite direction the delivery is moved toward the right, which movement is accompanied by riding of the follower 71 down the inclined cam 73 and consequent swinging of the frame 36 generally in the clockwise direction about the axis of the shaft 35 from the position shown in Figure 4 to the position shown in Figures 1 and 3. Continued movement of the delivery toward the press is unaccompanied by any relative movement between the delivery body and the frame 36 and the entire delivery moves rectilinearly into operative position relatively to the press.

When the frame 36 is swung up to the position shown in Figure 4 the tapes 60 and 62 are displaced to some extent around the shaft 35. The resilient mountings for the rollers 53 and 57 come into play at this point, allowing such rollers due to the added tension on the tapes to move resiliently toward the right. When the frame 36 again assumes its normal or horizontal position the tapes assume their normal position, as shown in Figure 1, and the rollers 53 and 57 move back toward the left to their normal positions under the action of the springs in their mountings. The structure and operation of the frame 36 and the tapes 60 and 62 form the subject matter of my copending application Serial No. 353,871.

Mounted in the delivery for pivotal movement about a transversely extending pivot 74 is a lever 75. Pivoted to the lever 75 at its lower end at 76 is a link 77 having a hook-shaped end 78. The press driving gear is shown diagrammatically in

Figure 1 at 79. It meshes with a gear 80 fixed to a shaft 81. Also fixed to the shaft 81 is a pinion 82 which meshes with a gear 83 fixed to a shaft 84. Also fixed to the shaft 84 is a crank 85 to which is pivoted at 86 a connecting rod 87. The opposite end of the connecting rod 87 is carried by a reciprocable crosshead having a crosshead pin 88 preferably carrying an anti-friction roller as shown. The hook 78 is adapted to hook over the crosshead pin 88. When the parts are thus engaged operation of the press which is accompanied by reciprocation of the crosshead pin 88 is also accompanied by oscillation of the lever 75.

Mounted in the delivery frame is a shaft 89 having fixed thereto a manually operable control handle 90 which is positioned outside the frame. Also fixed to the shaft 89 inside the frame is a pinion 91. Mounted in the delivery frame is a shaft 92 to which is fixed a gear segment 93 meshing with the pinion 91. Thus turning of the handle 90 causes through the pinion 91 and the segment 93 turning of the shaft 92 through a limited angle.

Fixed to the shaft 92 is an arm 94. Pivoted to the arm 94 at 95 is a link 96 having an elongated slot 97 in its opposite end. A stub shaft 98 is mounted in the delivery and has a bell crank lever 99 turnably mounted thereon. The bell crank lever has a generally downwardly extending arm 100 having at its extremity a pin 101 which enters the elongated slot 97 in the link 96. The bell crank lever 99 also has a generally laterally extending arm 102 to which is pivoted at 103 a generally downwardly extending rod 104 which in turn is pivoted to the link 77 at 105.

When the press and delivery are operating the cross-head pin 88 lies within the hook 78, as shown in Figures 1 and 3. When the delivery is to be moved away from the press the handle 90 is turned two revolutions in the counter-clockwise direction, viewing Figure 1. This, through the pinion 91 and the segment 93, causes rotation of the shaft 92 through a limited angle in the clockwise direction, viewing Figure 1. Such rotation of the shaft 92 pushes the link 96 toward the right against the pin 101 in the arm 100 of the bell crank lever 99 and turns such lever in the counter-clockwise direction about its axis 98. This lifts the rod 104, which raises the link 77 about its pivot 76 and disconnects the hook 78 from the crosshead pin 88. The link 77 is shown in Figure 4 as thus raised. In this manner the delivery drive is disconnected from the press so that the delivery can be moved away from the press.

When the delivery is to be moved back into cooperative relationship with respect to the press the handle 90 is first returned to the position shown in Figure 1. This lowers the link 77 to approximately the orientation shown in Figure 1 but as thus lowered the hook 78 is not engaged over the crosshead pin 88. Upon movement of the delivery toward the press the inclined nose surface 106 of the link 77 rides up on the crosshead pin 88, thus raising the right-hand end of the link 77 about its pivot 76. As the delivery continues movement toward the press the right-hand end of the link 77 is progressively raised until the hook 78 finally drops down over the crosshead pin 88. This movement of the link 77 is permitted by reason of the provision of the elongated slot 97 in the link 96, for when the right-hand end of the link 77 is raised by engagement of the inclined nose surface 106 with the cross-head pin 88 this pushes up the rod 104 and turns the bell

crank lever 93 to a limited extent in the counter-clockwise direction, during which movement the pin 101 simply slides freely in the slot 97. Also during operation of the mechanism when the crosshead pin 88 oscillates back and forth carrying the link 77 with it such oscillation is accompanied by slight up and down movement of the rod 104, which is permitted by the slot 97 which allows the pin 101 to ride freely therein during such movement.

Fixed to the shaft 92 is an eccentric 107. Surrounding the eccentric 107 is an eccentric strap 108 forming one end of an arm 109 having an upwardly facing hook 110 at its opposite end. Mounted in the delivery frame is a stationary fulcrum pin 111. The arm 109 has a lateral projection 112 which underlies the fulcrum pin 111. The arm 109 is normally urged upwardly by a coil spring 113 connected to the arm at 114 and to the delivery frame at 115. The press has a latch plate 116 with which the hook 110 is adapted to cooperate to mechanically latch the delivery to the press during operation.

As the parts are shown in Figure 1 the center of the eccentric 107 is generally to the left of the center of the shaft 92. As explained above in connection with the delivery driving mechanism, when the delivery is to be moved away from the press the handle 90 is turned through two revolutions in the counter-clockwise direction viewing Figure 1 and this turning of the handle is accompanied by rotation of the shaft 92 to a limited extent in the clockwise direction. Such clockwise turning of the shaft 92 swings the eccentric upwardly and toward the right viewing Figure 1. But since the fulcrum pin 111 is stationary such swinging of the eccentric causes the arm 109 to pivot about the fulcrum pin 111 and the hook or latch 110 moves downwardly and disengages from the latch plate 116 on the press. This severs the mechanical connection between the delivery and press and frees the delivery for movement away from the press.

When the delivery is away from the press and ready to be moved back toward the press the handle 90, eccentric 107 and arm 109 are moved to the position shown in Figure 1. As the delivery approaches the press the inclined forward surface 117 of the hook 110 rides down on the latch plate 116. For reasons presently to be explained the delivery ordinarily stops a fraction of an inch away from the press so that it does not move quite far enough for the arm 109 to swing back up under the action of the spring 113 to engage the latch 110 over the latch plate 116 as shown in Figure 1. When the parts are thus positioned the handle 90 is turned in the counter-clockwise direction somewhat less than two complete revolutions. This, as above explained, is accompanied by turning of the shaft 92 and movement of the center of the eccentric 107 generally upwardly and toward the right viewing Figure 1. But the lateral component of such movement moves the arm 109 as a whole to the right sufficiently for the latch 110 to clear the plate 116 and when this has occurred the spring 113 pulls up the latch into latching engagement with the plate 116. The handle 90 is then turned back in the clockwise direction to the position shown in Figure 1, which swings the eccentric 107 downwardly and toward the left. This tends to move the arm 109 to the left, but since the opposite end of the arm is firmly hooked or latched to the press the result is that during such clockwise turning of the handle 90 the delivery is by the arm 109

through the eccentric 107 drawn up firmly and tightly against the press.

While only a single arm 109 and associated mechanism have been described above I prefer 5 to employ two such arms, one adjacent each side of the delivery, the two arms being identical and operating synchronously. This causes the delivery and press to be drawn together firmly adjacent both side frames. The fastening mechanism is claimed in my divisional application, Serial No. 610,974, filed August 17, 1945.

It has been explained above that operation of the motor 25 in one direction or the other causes 15 rotation of the screws 16 and 18 to move the delivery toward or from the press. The motor circuit is controlled by four switches, one for closing the circuit to start the motor in one direction to move the delivery out, a second for opening such 20 circuit to stop outward movement of the delivery. The delivery being in the out position, the handle 25 90 is turned in the clockwise direction to the position of Figure 1. Fixed to the shaft 92 is a pair of switch operating arms 118 and 119. When the handle 90 is moved as above described the arm 118 operates a switch 120 which closes the motor 30 circuit to operate the motor in the direction to cause the delivery to move inwardly toward the press. The switch 120 is mounted on the frame of the delivery adjacent the shaft 92 and in position to be operated by the arm 118 upon movement 35 of the handle 90 as just explained. The delivery continues its inward movement until a switch operating member 121 on the press operates a switch 122 on the delivery which opens said motor circuit and stops inward movement of 40 the delivery toward the press. The switch 122 and switch operating member 121 are so positioned that the switch 122 is operated to stop the delivery a fraction of an inch before it reaches its fully operative position adjacent the press as 45 above explained. Thereafter manipulation of the handle 90 as above explained draws the delivery up tight against the press.

When the delivery is to be moved out away 50 from the press the handle 90 is turned to the position shown in Figure 4. This is done by turning the handle in the counter-clockwise direction from the position of Figures 1 and 3 through two revolutions. This causes the switch 55 operating arm 119 (see Figure 7) to swing upwardly and operate a switch 123 carried by the delivery adjacent the shaft 92 to close the circuit which operates the motor in the direction opposite that in which the delivery is moved in toward the press. Consequently the delivery moves 60 outwardly away from the press. This movement, as above explained, is accompanied by downward movement of the link 67. Such link carries a switch operating arm 124, which when the delivery has reached its full outward position operates a switch 125 carried by the delivery adjacent the link 67. Operation of the switch 125 opens the circuit and the delivery stops.

The handle 90 controls the motor for moving 70 the delivery, the driving connection between the delivery and press and the mechanical connection or latch for holding the delivery in place against the press. When the delivery is in, as shown in Figure 1, turning of the handle 90 through two revolutions in the counter-clockwise direction releases the latch 110, disconnects the

driving connections 78 and finally initiates operation of the motor to move the delivery out. The handle 90 also initiates operation of the motor to move the delivery in and positions the arm 109 and the link 11 to adapt them to cooperate with the press when the delivery moves in. The delivery automatically stops a fraction of an inch short of its ultimate position and again the same handle 90 simply by being turned somewhat less than two revolutions first in the counter-clockwise direction from the position shown in Figure 1 and then back in the clockwise direction to that same position causes the hook 110 to draw the delivery firmly up against the press, this operation being accompanied by dropping of the hook 78 over the crosshead pin 83 to render the delivery operable from the press drive. Thus a minimum of manual effort is needed to move the delivery toward and from the press.

The lever 75 carries at its upper end a gear segment 126 which meshes with a pinion 127 fixed to a shaft 128. Also fixed to the shaft 128 is a gear 129 and another gear 130. The gear 130 meshes with a pinion 131 fixed to a shaft 132. Also fixed to the shaft 132 is a pair of sprockets 133, one adjacent each side frame. Carried by each of the side frames of the delivery is a stud 134. Each stud 134 carries interiorly of the side frame with which it is connected a sprocket 135. Each sprocket 135 is in alignment with one of the sprockets 133. A sprocket chain 136 at each side of the delivery meshes with one of the sprockets 133 and the aligned sprocket 135. Each of the sprocket chains 136 passes over idler sprockets 137, one or both of which may be adjusted for tensioning the chain.

Each of the sprocket chains 136 has one or more special links 138, the special links in the respective chains being positioned opposite each other. Each of such special links has ears 139 to which is connected a bracket 140 having rollers 141 riding upon longitudinal tracks 142. The opposed brackets 140 are connected by cross members 143 to form a carriage oscillatable on the tracks 142 by the sprocket chains 136. The oscillatory movement of the segment 126 is transferred through the gear 127, the shaft 128, the gear 130, the pinion 131, the shaft 132 and the sprockets 133 to the sprocket chains 136 and thence to the carriage itself. Thus during operation of the mechanism the reciprocable delivery carriage moves back and forth longitudinally of the delivery and toward and from the press upon the tracks 142. The carriage carries sheet handling means including tapes 144 cooperating with the tapes 60 and 62 to receive and deliver sheets, but since such means form no part of the present invention they will not be described in detail. Suffice it to say that the reciprocable delivery carriage ordinarily receives a sheet from the tapes 60 and 62 upon each reciprocation thereof and delivers the same to the delivery pile.

Meshing with the gear 129 is a segment 145 fixed to a sleeve 146. The sleeve 146 is journaled for angular oscillation upon a shaft 147. The sleeve 146 passes through the delivery side frame as shown in Figure 11 and carries at its outer end an arm 148. Since the segment 145 and the arm 148 are both fixed to the sleeve 146 they are to all intents and purposes unitary. The arm 148 carries a pawl 149 projecting laterally therefrom and engaging a ratchet 150 fixed to the shaft 147. The pawl is normally resiliently urged into engagement with the ratchet 150 by a coil spring 151. Upon oscillation of the segment 145

5 the pawl 149 advances the ratchet 150 and, consequently, the shaft 147 to which it is fixed, step by step. Means forming no part of the present invention are provided for adjusting the arc through which the pawl moves the ratchet upon each oscillation of the segment 145.

Fixed to the shaft 147 is a pinion 152. Such pinion meshes with a gear 153 which, in turn, meshes with a gear 154 fixed to a shaft 155. Also fixed to the shaft 155 is a bevel gear 156 meshing with a bevel pinion 157 fixed to a shaft 158 carrying a worm 159 meshing with a worm wheel 160. The worm wheel 160 is mounted loosely for rotation upon a shaft 161. Integral with the worm wheel 160 is a ratchet 200. Fixed to the shaft 161 is an arm 201 which pivotally carries at 202 a pawl 203 engaging the teeth of the ratchet 200. The pawl 203 is urged into engagement with the ratchet 200 by a compression coil spring 204. Thus when the worm wheel 160 and the ratchet 200 integral therewith turn in the counter-clockwise direction viewing Figure 12 the ratchet engages the pawl 203 and through such pawl turns the arm 201 therewith. But since the arm 201 is fixed to the shaft 161 such turning of the worm wheel and ratchet also turns the shaft 161. Also fixed to the shaft 161 is a pair of drums 162, one adjacent each side frame. A pair of cables is adapted to be wound up on and paid out by each of said drums 162. One of said cables 163 passes over a sheave 164 and thence downwardly to the pile support 165. The other 166 of said cables passes over a pair of sheaves 167 and 168 and thence downwardly to the pile support 165. Thus through oscillation of the lever 75 and the mechanism above described the delivery pile support is lowered step by step.

The gearing above described for lowering the pile support is enclosed within a casing 205 applied to the outside of the side frame of the delivery. The shaft 161 extends through the casing 205 and has a reduced extremity 206 provided with a pin 207. A handle is adapted to be applied over the reduced extremity 206 and engage with the pin 207 to turn the shaft 161 in the counter-clockwise direction viewing Figure 12, whereby manually to raise the pile support 165. When the pile support is thus raised the pawl 203 simply passes over the teeth of the ratchet 200 so that the position of such ratchet and the worm wheel 160 integral therewith is not disturbed.

Fixed to the shaft 128 is a cam 169. Journaled in the delivery frame is a shaft 170 on which is loosely mounted for rotation an arm 171 carrying at its extremity a roller 172 adapted to lie against and follow the cam 169. The arm 171 is urged down toward the position in which the roller 172 engages the cam 169 by a tension coil spring 208 acting between the arm 171 and a pin 209 carried by the delivery frame. Fixed to the shaft 170 at each side of the delivery is a generally upwardly extending arm 173. Fixed to the shaft 170 is an arm 210 having a laterally projecting pin 211. The pin 211 is adapted to lie against a generally upwardly projecting finger 212 integral with the arm 171 which, as above stated, is loose on the shaft 170. A compression coil spring 213 surrounds a guide rod 214 connected with a hub 215 pivoted to the arm 171 and passing through an opening 216 near the upper end of the arm 210. The spring 213 bears between the arm 210 and the hub 215, thereby urging the pin 211 into contact with the finger 212.

A jogger operating rod 174 is pivoted to each of the arms 173 at 217 and is adapted to be oscillated

lately moved thereby in a direction generally longitudinally of the delivery upon oscillation of the shaft 170. Fixed to the shaft 170 is a generally horizontally extending arm 175. Such arm underlies an eccentric turnable cam-like stop member 176 fixed to a shaft 177 passing through the delivery side frame and having a control arm 178 fixed thereto and disposed outside the side frame. The position of the stop member 176 is determined by the position of the control arm 178 which may be moved to any one of a plurality of adjusted positions and maintained therein by means of a spring pin 179 in the arm 178 which may enter any one of a plurality of arcuately arranged openings 180 in a plate 181 fastened to the outside of the side frame. The stop member 176 determines the extent to which the shaft 170 may turn in the clockwise direction viewing Figure 1.

Connected with the jogger operating rods 174 are rear jogger carriers 182 carrying rear joggers 183. Each of the rods 174 is pivoted at 184 to a bell crank lever 185 pivoted to the frame at 186 and having an arm 187 operating a transversely slidable rod 188. The respective rods 188 at opposite sides of the delivery move always in opposite directions, that is, both of such rods at any given time move inwardly or outwardly. Each rod 188 has fixed thereto a bracket 218 carrying a rearwardly extending rod 219 carrying side joggers 189 and the rear end of which rests upon a transverse member 220 and has a downturned extremity 221 positioned rearwardly of the member 220. The delivery pile 190 is guided at its outer edge by stationary guides 191 and is adapted to be jogged in the usual manner by the rear joggers 183 and the side joggers 189.

The cam 169 oscillates continuously during operation of the mechanism. When the roller 172 rides up on the high part of the cam 169 the arm 171 is swung in the counter-clockwise direction viewing Figure 1, and the spring 213 moves the arm 210, and with it the shaft 170 to which the arm 210 is fixed, in the counter-clockwise direction, thus moving the jogger operating rods to the left and moving all of the joggers inwardly toward the pile. When the joggers strike the edges of the pile they are arrested thereby and movement toward the left of the rods 174 stops. This is true even if the roller 172 has not yet reached the highest point of the cam 169 as the spring and pin connection between the lever 171 and the arm 210 permits further swinging of the arm 171 without an accompanying turning of the shaft 170. When the roller 172 rides down onto the low part of the cam 169 the spring 208 pulls the arm 171 downwardly or in the clockwise direction about the axis of the shaft 170, viewing Figure 1, and thus, through the engagement of the finger 212 against the pin 211, turns the shaft 170 in the clockwise direction and pulls the joggers outwardly away from the pile. This outward movement of the joggers continues as long as the shaft 170 continues to turn. The extent to which such shaft may turn in the clockwise direction is determined by the position of the stop member 176. Thus the stop member 176, which is controlled by the arm 178, controls the amplitude of oscillation of the joggers. If it is desired that the amplitude of oscillation of the joggers be less than the maximum amplitude provided for by the design of the cam 169, the control arm 178 is shifted to a position to swing the stop member 176 downwardly. When the shaft 170 turns in the clockwise direction in response to the action of the spring 208 during the time the roller 172

is riding from the high point to the low point of the cam 169 such turning will be interrupted when the arm 175 strikes the stop member 176. But since the arm 210 is fixed to the shaft 170 the pin 211 will prevent the arm 171 from following the cam 169 down to its lowest point, and the roller 172 will stop in mid air until it is engaged by the cam 169 upon the subsequent turning movement thereof in the clockwise direction viewing Figure 1.

Through the mechanism above described oscillation of the lever 75 carrying the segment 126 operates the joggers while provision is made for adjustment of the amplitude of oscillation of the joggers by a rapidly shiftable control member on the outside of the delivery frame. The joggers are operated through an oscillatory cam and the means for controlling the amplitude of oscillation of the joggers predetermines the portion of the normally effective surface of the cam which operates to move the joggers. The joggers are resiliently urged both toward and from the pile so that they will yield to any obstruction encountered in movement in either direction without damage thereto. This structure is described and claimed in my copending application Serial No. 386,652, filed April 3, 1941, which has matured into Patent No. 2,371,190.

The parts are so related that when the cross-head pin 88 is at its extreme right-hand position viewing Figure 1 and, consequently, when the lower end of the lever 75 is in its extreme right-hand position, the reciprocable carriage carried by the sprocket chains 136 is at its extreme left-hand position. During operation of the delivery the carriage oscillates back and forth and its position always bears a predetermined relation to the position of the lever 75. When the carriage is at its right-hand position the tapes 144 extend in between the tapes 62 of the frame 36 and over a portion of the press. When the delivery is to be moved away from the press it is desirable that the carriage carrying the tapes 144 be moved to its left-hand position viewing Figure 1. However, the crosshead pin 88 may stop in any position between the limits of its longitudinal travel when the driving motor circuit is opened.

In order to insure that when the delivery is to be moved away from the press the carriage will assume its left-hand position farthest from the press the lever 75 is provided with a cross pin 195. Fastened to the cross pin 195 and extending generally longitudinally of the delivery is a pin 196 which is loosely guided in an opening 197 in the delivery frame. A coil spring 198 surrounds the pin 196 and bears between the pin 195 and the frame. When the press driving motor has been stopped and the delivery is to be moved away from the press and the handle 90 is turned in the counter-clockwise direction as above explained to disconnect the hook 78 from the crosshead pin 88, if the reciprocable delivery carriage is not already in its left-hand position (corresponding to the extreme right-hand position of the crosshead pin 88), as soon as the portion 199 of the link 77 has been raised above the center of the crosshead pin 88 the spring 198 will push the lower end of the lever 75 toward the right until it strikes a limiting stop (not shown). When the lever 75 is in such position the carriage is in its extreme left-hand position.

Consequently upon operation of the handle 90 when the delivery is to be moved away from the press the reciprocable delivery carriage is caused automatically to assume its extreme left-hand

position most remote from the press regardless of the position in which the crosshead pin 88 stops. If the crosshead pin 88 should stop at or near its extreme left-hand position viewing Figure 1 the spring 193 would operate as above described to move the carriage toward the left. Then when it should be desired to move the delivery back into cooperative relationship with respect to the press the link 77 would be lowered by operation of the handle 90 as above explained. Upon movement of the delivery toward the press the portion 106 of the link 77 would ride up on the crosshead pin and the hook 78 would become engaged therewith, as above explained, whenever the hook should reach the crosshead pin irrespective of the exact position of the crosshead pin and after engagement of the hook 78 with the crosshead pin the relative position of the parts of the drive would be fixed so that upon starting of the press driving motor the press and delivery would operate in proper synchronism. Thus the handle 90 not only controls the driving connection between the press and delivery, the latch for latching the press and delivery together and the switches for starting the delivery moving motor, but its operation also results in movement of the reciprocable delivery carriage to its extreme left-hand position when the delivery is to be moved away from the press, as above explained.

The handle 90 has a grip portion 192 having an inwardly projecting pin 193 urged inwardly by a spring (not shown). The side frame carries a hollow outward projection 194 into which the pin 193 is adapted to project when the handle is stationary to hold it in position. To operate the handle the grip portion 192 is grasped and pulled outwardly and the handle turned and after completion of the turning operation the pin 193 is positioned opposite the hollow outward projection 194 and the grip portion 192 released to hold the handle in place.

The construction above described is such that all of the operating mechanism for operating the delivery carriage, operating the joggers and raising the frame carrying the conveyor which extends toward the press, as well as the driving connections between the delivery and press, the mechanical connections therebetween and the operating means for said connections lie laterally of the apparatus between the outer surfaces of the side frames of the delivery. Indeed, the only operating mechanism projecting beyond the side frames is the pile support lowering mechanism, but this mechanism is of such nature that it can readily be enclosed within a casing. Thus, there are no moving parts exposed outside the side frames of the delivery which might cause damage or inconvenience in operation of the mechanism.

While I have shown and described a present preferred embodiment of the invention it is to be distinctly understood that the same is not limited thereto but may be otherwise variously embodied within the scope of the following claims.

I claim:

1. Material handling apparatus comprising a base, handling mechanism adapted when operative to be fastened to the base, the handling mechanism having a portion adapted to assume positions at various distances from the base in operation of the handling mechanism, and means operable to unfasten the handling mechanism from the base and position said portion of the handling mechanism predeterminedly relatively

to the base if the same is not already so positioned.

2. Material handling apparatus comprising a movable portion adapted to traverse a predetermined path in operation of the apparatus and to stop at any of a number of positions when operation of the apparatus is stopped and means operable after operation of the apparatus has been stopped effective to move said movable portion of the apparatus to a predetermined part of said path if said movable portion did not happen to stop at said part of said path.

3. Material handling apparatus comprising operating mechanism for operating on material and handling mechanism adapted to cooperate with the operating mechanism to handle the material, the handling mechanism comprising a movable portion adapted to traverse a predetermined path in operation of the handling mechanism and to stop at any of a number of positions when operation of the handling mechanism is stopped, the operating mechanism and handling mechanism being separable when not in use, and means operable after operation of the handling mechanism has been stopped effective to move said movable portion of the handling mechanism to a part of said path distant from said operating mechanism if said movable portion did not happen to stop at said part of said path.

4. Material handling apparatus comprising a base, handling mechanism adapted to assume operative and inoperative positions relatively to the base, the handling mechanism having a portion adapted to assume positions at various distances from the base in operation of the handling mechanism and means operable to position said portion of the handling mechanism predeterminedly relatively to the base if the same is not already so positioned and separate the handling mechanism and base so that the handling mechanism is in inoperative position relatively to the base.

5. Material handling apparatus comprising a base, handling mechanism adapted to assume operative and inoperative positions relatively to the base, the handling mechanism having carrying means adapted to move within the handling mechanism in operation of such mechanism, and means including a single control device for positioning the carrying means predeterminedly within the handling mechanism if the same is not already so positioned, and separating the handling mechanism and base so that the handling mechanism is in inoperative position relatively to the base.

6. Material handling apparatus comprising a base, handling mechanism adapted when operative to be fastened to the base but separable from the base when inoperative, the handling mechanism having carrying means adapted to move within the handling mechanism in operation of such mechanism, and means including a single control device for unfastening and separating the handling mechanism from the base and positioning the carrying means predeterminedly within the handling mechanism if the same is not already so positioned.

7. Material handling apparatus comprising a base, handling mechanism adapted when operative to be fastened to the base, the handling mechanism having carrying means adapted to move within the handling mechanism in operation of such mechanism, and means including a single control device for unfastening the handling mechanism from the base and positioning the carrying means predeterminedly within the

handling mechanism if the same is not already so positioned.

8. Sheet delivery apparatus comprising a base, delivery mechanism adapted when operative to be fastened to the base, the delivery mechanism having an oscillatable carrier, and means including a single control device for unfastening the delivery mechanism from the base and positioning the carrier predeterminedly within the delivery mechanism if the same is not already so positioned.

9. Printing or like apparatus comprising mechanism for printing or similarly operating on sheets, delivery mechanism for delivering sheets relatively to the first mentioned mechanism and adapted when operative to be fastened to the first mentioned mechanism but separable therefrom when inoperative, the delivery mechanism having an oscillatable carrier, and means including a single control device for unfastening and separating the delivery mechanism from the first mentioned mechanism and positioning the carrier predeterminedly within the delivery mechanism if the same is not already so positioned.

10. Material handling apparatus comprising material handling mechanism including movable material handling means, driving means for said material handling means mounted separately from said material handling mechanism and connectable with said material handling means, means for disconnecting the material handling means and driving means, separating the material handling mechanism and driving means and moving the material handling means to predetermined position relatively to the material handling mechanism and a single control device for controlling operation of said last mentioned means.

11. Material handling apparatus comprising material handling mechanism including material handling means, driving means for said material handling means mounted separately from said material handling mechanism and connectable with said material handling means, means for fastening said material handling mechanism in operative relationship to said driving means, means for rendering inoperative said fastening means, disconnecting the material handling means and driving means and separating the material handling mechanism and driving means and a single control device for controlling operation of said last mentioned means.

12. Material handling apparatus comprising material handling mechanism including material handling means, driving means for said material handling means mounted separately from said material handling mechanism and connectable with said material handling means, means for fastening said material handling mechanism in operative relationship to said driving means, means for rendering inoperative said fastening means, disconnecting the material handling means and driving means, separating the material handling mechanism and driving means and moving the material handling means to predetermined position relatively to the material handling mechanism and a single control device for controlling operation of said last mentioned means.

13. Sheet delivery apparatus comprising delivery mechanism including a carrier, driving means for the carrier mounted separately from the delivery mechanism and connectable with the carrier, means for fastening the delivery mechanism in operative relationship to the driving means, means for rendering inoperative said fas-

tening means, disconnecting the carrier and driving means, separating the delivery mechanism and driving means and moving the carrier to predetermined position relatively to the delivery mechanism and a single control device for controlling operation of said last mentioned means.

14. Material handling apparatus comprising a bodily movable portion, means including motive means for moving said portion in a predetermined path, a switch for rendering the motive means operative to move said portion in one direction, another switch for rendering the motive means operative to move said portion in the opposite direction and control means including a manually operable crank and a rotary control member operated by said crank and having means whereby upon movement of the crank to one position it operates one of the switches and upon movement of the crank to another position it operates the other switch.

15. Material handling apparatus comprising a frame, an oscillatable endless element carried by the frame, a gear segment also carried by the frame for oscillating said endless element, driving means separate from the frame and displaceable relatively thereto and a connection between said driving means and said gear segment whereby said gear segment is oscillated, said connection being readily disconnectable to permit relative displacement between said frame and said driving means.

16. Material handling apparatus comprising an oscillatable carrier, a gear segment for oscillating the carrier, driving means including an oscillatable crosshead and a connection between the gear segment and driving means pivoted to the gear segment and having a readily disconnectable connection with the crosshead.

17. In combination, driving mechanism and driven mechanism, said mechanisms being separable, a driving connection between said mechanisms, means for fastening said mechanisms together, means for disconnecting said driving connection, means for unfastening said fastening means, means for separating said driving mechanism and driven mechanism and a single control device for actuating a plurality of the three means last mentioned.

18. In combination, driving mechanism and driven mechanism, said mechanisms being separable, a driving connection between said mechanisms, means for fastening said mechanisms together, means for disconnecting said driving connection, means for unfastening said fastening means, means for separating said driving mechanism and driven mechanism and a single control device for actuating all of the three means last mentioned.

19. In combination, driving mechanism and driven mechanism, said mechanisms being separable, a driving connection between said mechanisms, means for fastening said mechanisms together, means for disconnecting said driving connection, means for unfastening said fastening means, means for separating said driving mechanism and driven mechanism, an operating shaft and connections with said shaft operable upon rotation thereof for actuating a plurality of the three means last mentioned.

20. Material handling apparatus comprising driving means, material handling mechanism separable from said driving means, said mechanism including an oscillatable carrier, an oscillatable endless driving element for driving said carrier and a connection from said driving element to

said driving means, said connection being severable upon separation of said material handling mechanism and driving means.

21. In combination, material handling apparatus, means for assembling the material handling apparatus with and separating the same from cooperating mechanism, a portion of the material handling apparatus being so constructed and arranged as to be generally vertically movable during relative assembling and separating movement between the material handling apparatus and the cooperating mechanism, and means for rendering inoperative said first mentioned means upon relative movement between the material handling apparatus and the cooperating mechanism, said second mentioned means being operated by said portion of the material handling apparatus when the same has been generally vertically moved to a predetermined extent.

22. Sheet handling apparatus for handling sheets relatively to a press or the like comprising side frame members, a reciprocable sheet handling carriage, endless conveyor means and means for reciprocating said carriage and driving said endless conveyor means disposed laterally of the

apparatus within the space defined by the outer surfaces of the side frame members.

23. In combination, a pair of mechanisms adapted to cooperate when in assembled relationship and relatively bodily movable, means for relatively moving said mechanisms to assemble them, means for fastening said mechanisms together when in assembled relationship and a control device operable to initiate operation of said means for relatively moving said mechanisms to assemble them and operable when said mechanisms are in approximately assembled relationship to operate said fastening means to draw said mechanisms firmly together.

24. In combination, a pair of mechanisms adapted to cooperate when in assembled relationship and relatively bodily movable, means for relatively moving said mechanisms, a connection operable between said mechanisms when said mechanisms are assembled and a control device initiating relative movement of said mechanisms to assemble them and to separate them and also controlling said connection.
